DESIGN FOR A TARGET

Louis G. La Borie, Rochester, N. Y.

Application March 27, 1934, Serial No. 51,202

Term of patent 3½ years

To all whom it may concern:

Be it known that I, Louis G. La Borie, a citizen of the United States, residing at Rochester, in the county of Monroe and State of New York, have invented a new, original, and ornamental Design for a Target, of which the following is a specification, reference being had to the accompanying drawing, forming part thereof.

In the drawing:

The figure is a face view of a target, showing my new design.

The article is of no appreciable depth, being of the thickness of cardboard.

I claim:

The ornamental design for a target, as shown and described.

LOUIS G. LA BORIE.
